UNITED STATES PATENT OFFICE.

BERT E. DUGGAN, OF TELLURIDE, COLORADO.

SLIME-SAVING DEVICE FOR ORE-CONCENTRATORS.

No. 889,800.

Specification of Letters Patent.

Patented June 2, 1908.

Application filed March 19, 1907. Serial No. 363,198.

To all whom it may concern:

Be it known that I, BERT E. DUGGAN, a citizen of the United States, residing at Telluride, in the county of San Miguel and State of Colorado, have invented certain new and useful Improvements in Slime-Saving Devices for Ore-Concentrators, of which the following is a specification, reference being had therein to the accompanying drawing.

10 My invention relates to improvements in ore concentrating apparatus and more particularly to a device for use in connection with concentrating tables, or the like, for collecting and saving the slimes which carry floating gold or other metal, or any other valuable substance which is not saved by the present concentrators.

15 The object of the invention is to provide a simple and practical device of this character which will skim the slime from the pulp passing over the concentrating table and direct it into a suitable settling box or tank.

20 Another object of the invention is to provide a device of this character in the form of an attachment which may be readily applied to concentrators now in use and which may be adjusted to effect the desired result.

25 Further objects and advantages of the invention, as well as the structural features by means of which these objects are attained, will be made clear by an examination of the following specification, taken in connection with the accompanying drawings, in which

30 Figure 1 is a plan view of the rear or tailings end of a well known form of concentrator showing the application of my invention thereto; Fig. 2 is a side elevation of the same, with parts in section; Fig. 3 is an end view; Fig. 4 is a perspective view of the slime skimming device; Fig. 5 is a detail section taken on the plane indicated by the line 5—5 in Fig. 1; and Fig. 6 is a vertical section taken on the plane indicated by the line 6—6 in Fig. 1.

35 While my invention may be adapted for use upon an ore concentrator of any description it is here shown applied to one of the well known form having a stationary frame 1 and a movable frame 2 suitably mounted for 40 either reciprocatory or swinging movement in either vertical or horizontal planes and which carries an endless belt or band 3 forming the concentrator table and passing over suitable drums or rollers. The movable frame 2 is here shown as supported above the stationary frame by resilient uprights 2^a but

it may be otherwise mounted. Any suitable means may be provided for actuating the frame 2 but the one illustrated consists of a tappet wheel or disk 2^b fixed upon a rotatable 60 shaft 2^c and adapted to engage a block or projection 2^d fixed upon said frame 2.

65 My invention consists in a suitable means mounted above the concentrator table and adapted to skim the slime from the pulp passing over the table and direct the slime to a suitable collecting or settling tank or receptacle. The skimming device 4 illustrated in the drawings is substantially Y-shaped and comprises two diverging deflector arms 5 70 which project from the inner end of a trough or spout 6. As shown in Fig. 4, the parts 5, 6 are formed from a single piece of sheet metal, the spout 6 being of rectangular form 75 in cross section and having outwardly projecting horizontal flanges 7, and the arms 5 being angular in cross section having horizontal flanges 8 forming continuations of the flanges 7, and forwardly and downwardly inclined portions or plates 9 which are adapted 80 to project into the pulp passing over the concentrator table for the purpose of skimming the slime therefrom and direct it into the trough or spout 6. While the present embodiment of the invention comprises a single 85 spout arranged between two deflecting arms it will be understood that any number of such spouts and arms may be used and that the parts may be of any shape to accomplish the 90 desired result.

90 The skimming device 5 is adjustably supported above the top of the concentrating table by securing its horizontal flanges 7, 8 by means of bolts, or the like, 10 to the bottom faces of two cross bars 11 which have 95 their ends supported by adjustable uprights 12. The latter are shown in the form of screw rods having their ends screw threaded in opposite directions, their lower ends 13 working in nuts 14 arranged in the stationary frame 1 and their upper ends 15 passing through threaded apertures 16 formed in the ends of the bars 11. Intermediate the ends of these adjusting screws are flattened enlargements 17 which permit them to be readily turned for the purpose of adjusting the bars 11 and hence the skimming device. In order to prevent any of the pulp and slime passing down the concentrating table from 100 passing around the ends of the deflector arms 5 as said table is oscillated or reciprocated and to prevent the movement of the same

from being imparted to the device 4, I provide strips 18 of flexible metal, rubber, or the like, between the movable frame 2 and the ends of the arms 5, as clearly shown in Fig. 1. 5 I may also employ supplemental deflectors 19 for directing the pulp and slimes toward the center of the concentrating table. These deflectors 19 are preferably in the form of strips of wood supported above the table and connected to the movable frame 2 by spring plates 20 or any other resilient fastening means.

The slimes passing through the spout 6 are discharged from its outer end into a spout or 15 launder 21 which directs it into a suitable settling box or tank 22. The latter is here shown in the form of a rectangular box having a discharge spout 23 at one of its ends and having the spout 21 arranged to discharge the slime into its opposite end. Arranged vertically in the tank or box are one or more vertical wings or partitions 24 which have their lower ends spaced from the bottom of the tank so that the slimes in order to 20 pass out of the discharge 23, must drop to the bottom of the tank, thus insuring a complete settling.

The operation of the invention will be readily understood from the foregoing description. It will be noted that the device may be readily applied to any form of concentrator and that when once applied it may be readily adjusted so that the deflector arms 5 will skim the desired quantity of slime from 35 the pulp. The device is especially designed for saving slimes containing valuable minerals or chemical substances, which owing to their tendency to float on or near the surface of the pulp are carried away by the slime and are 40 not saved by the concentrating devices now in use.

Having thus described my invention what I claim and desire to secure by Letters Patent is:—

45 1. The combination of a stationary frame, a movable frame, a concentrator table arranged upon said movable frame, a pair of cross bars arranged above the table and having their ends formed with threaded apertures, nuts arranged upon the main frame, upright screw rods having centrally arranged flattened enlargements and oppositely screw threaded ends, their upper ends being engaged with apertures in the cross bars and 50 their lower ends with said nuts, a slime skimming device arranged above the table and

having a Y-shaped body, one of its branches being trough shaped to provide a discharge spout and its other two branches being angular in cross section and having horizontal 60 flanges engaged with the bottom faces of said cross bars, and bolts securing said flanges to the cross bars, substantially as set forth.

2. The combination with a movable ore concentrator frame and its table, of a stationary slime skimming device and a flexible element between one end of said device and said concentrator for preventing the pulp upon the table from passing around said end of the skimming device. 70

3. The combination with a movable ore concentrator frame and its table, of a stationary frame, a slime skimming device carried by said stationary frame and arranged above said table, and a deflector carried by said stationary frame and arranged above the table to direct the pulp thereon into said skimming device. 75

4. The combination with a movable ore concentrator frame and its table, of a stationary frame, a slime skimming device carried by said stationary frame and arranged above said table, and a deflector yieldably connected to said stationary frame and arranged above the table in advance of said skimming 85 device to direct the pulp upon the table into said device.

5. The combination with a concentrator having a stationary frame and a movable frame carrying a concentrating table, of a 90 slime skimming device to co-act with said table, said device having a spout and diverging deflector arms, means for supporting said device from said stationary frame and flexible connections between the ends of said deflector arms and said movable frame. 95

6. The combination with a concentrator having a stationary frame and a movable frame carrying a concentrating table, of a 100 slime skimming device to co-act with said table, said device having a spout and diverging deflector arms, means for supporting said device upon said stationary frame and deflectors carried by said movable frame for directing the pulp between said diverging deflector arms. 105

In testimony whereof I hereunto affix my signature in presence of two witnesses.

BERT E. DUGGAN.
